COFFERDAM

Starling Perkins, Chouteau, Okla.

Application August 29, 1947, Serial No. 771,269

2 Claims. (Cl. 61—82)

1

This invention relates to coffer-dams such as used in sinking shafts, tunneling and other operations requiring a casing for holding back the earth and fluids through which the project is extended. Usually such coffer-dams require a pressure chamber for holding back external pressures and an air lock chamber is required for access to and exit from the pressure chamber. Such structures are very expensive, difficult to assemble, require the workmen to operate under high pressures, and are difficult and oftentimes impossible to salvage when the work is completed.

It is, therefore, the principal object of the present invention to provide a relatively simple structure for any coffer-dam use and which is composed of readily interconnected sections that may be readily handled and shipped to a site of operations for simple assembly and which sections are equipped with excavating jets and other equipment to effect placement of the coffer-dam and operations that are to be performed therewith.

Other objects of the invention are to maintain the flow of pressure fluids after the coffer-dam is in position to prevent entrance of external fluids while the soil is being removed from the interior of the coffer-dam; to provide a coffer-dam structure wherein the weight thereof is supplemented by weight of liquids adapted to be injected within the compartments of the respective sections and from which the liquids are adapted to be pumped for controlling sinking of the coffer-dam; to provide a coffer-dam with means for freezing the soil and fluids at the base thereof to assist in drying up the interior so that the soil may be excavated and the desired structures built therein; and to provide a coffer-dam constructed to facilitate ready removal thereof after the work has been completed.

In accomplishing these and other objects of the invention hereinafter pointed out, I have provided improved structure, the preferred form of which is illustrated in the accompanying drawings wherein:

Fig. 1 is a vertical sectional view through a coffer-dam constructed in accordance with the present invention and showing the manner of sinking the coffer-dam structure into an earth formation.

Fig. 2 is a detail fragmentary view through adjacent sections of the coffer-dam, illustrating the interlocking connection thereof.

Fig. 3 is a fragmentary perspective sectional view through one of the coffer-dam sections, particularly illustrating the construction thereof.

Fig. 4 is a section through a modified form of the invention showing refrigerating coils in the lower compartment.

Referring more in detail to the drawings:

1 designates a coffer-dam constructed in accordance with the present invention and which

may be of any suitable cross sectional shape to conform with the shaft to be sunk into an earth formation; however, the coffer-dam is preferably of cylindrical shape and the wall structure may comprise two or more sections depending upon the size of the dam. For example, in the illustrated instance, the coffer-dam comprises a pair of semi-cylindrical sections 2 and 3 joined at opposite diametrical sides of the dam by interlocking slideable connections 4 later described. Each section includes an inner wall sheet 5 preferably composed of sheet metal in semi-cylindrical shape to form the inner contour of the coffer-dam.

Extending along the outer side of the inner wall 5 are a plurality of vertically spaced angles 6, 7, 8, and 9 which are shaped to conform with the outer contour of the inner wall and which have horizontal flanges 10, 11, 12, and 13 respectively. The flanges 10 and 13 of the upper and lower angles 6 and 9 are welded or otherwise suitably attached to the upper and lower edges of the inner wall and the intermediate angles 7 and 8 have the horizontal flanges 11 and 12 thereof similarly welded to the inner wall to provide leak-tight joints. The other legs 14, 15, 16 and 17 of the respective angles extend downwardly in spaced relation with the inner wall for attaching an outer wall sheet 18 which is preferably composed of a plurality of segmental rings 19, 20, 21 and 22 having the upper and lower edges in abutting relation and overlapping the flanges 14, 15, 16 and 17 of the respective angles so that the edges of the plates may be welded together and to the flanges to provide leak-tight joints between compartments 23, 24, and 25 that are provided between the respective angles.

The connections 4 each include mating members 26 and 27 of substantially corresponding shape but arranged reversely with respect to the positions they occupy in the respective sections of the coffer-dam. Each member of an interlocking connection comprises a transverse plate portion 28 of sufficient width to extend across the space between the inner and outer walls of the coffer-dam sections for closing the ends of the respective compartments. Coextensive with one side of the transverse plate 28 is a flange portion 29 that extends laterally therefrom and has a coextensive rib portion 30 on its outer edge and extending in the same direction and parallel with the plate portion 28. The rib 30 is spaced from the plate portion 28 to provide a channel-like groove 31 extending from the flange 13 of the lower angle member to the flange 13 of the upper angle member. Also extending laterally from the plate portion 28 intermediate the ends thereof, in the same direction and substantially parallel with the flange 28 is a tongue portion 32 having a T-shaped head portion 33 that is

coextensive with the rib portion 30 and is spaced therefrom to provide a vertical slot-like way 34. The head 33 thus cooperates with the tongue 32 to form vertical grooves 35 and 36 on opposite sides thereof in lateral alignment with the groove 31. The connection member thus described has a cross section substantially the shape of the letter F and the complementary connecting member is reversely arranged with respect thereto so that the flange portion 29 of one member is adapted to be welded to the inner face of an extension of the outer wall member of one coffer-dam section and the corresponding flange of the other member is welded to an extension of the inner wall of the other coffer-dam section. The opposite side edge of the plate portions of the connecting members are respectively welded to the inner and outer walls of the respective adjacent ends of the coffer-dam section as clearly shown in Fig. 2. The ends of the compartments are thus closed from each other and consequently each coffer-dam section must be provided with its own supply ducts and manifolds as later described.

Suitable clearance is preferably provided between the interlocking portions of the respective connecting members so that the joints may be filled with a heavy grease to facilitate sliding movement of the coffer-dam sections relatively to each other when the sections are to be removed as later described. The grease also retards leakage through the joints and prevents infiltration of external pressure fluids.

The flange 14 of the lower angle member depends downwardly and cooperates with the lower edge of the lowermost plate of the outer wall to provide a cutting edge 37 which may be reinforced on the inner side of the leg 14 by a plate 38 as best shown in Figs. 2 and 3. The plates forming the wall portion closing the outer side of the lower compartments 23 have a plurality of apertures 39 that are covered on the inner side by a plurality of layers preferably of non-corrosive wire screen 40 that are retained in position by a cover plate 41 having apertures 42 registering with the apertures 39 as best shown in Fig. 2. The plate 41 is preferably welded in position as indicated at 43. The lower portion of the inner wall sheet 5 of each coffer-dam section is provided with a plurality of similar apertures 44 covered by layers of screening 45 that are retained in position on the inner side of the wall sheet by an apertured retaining plate 46. The apertures 44 are located adjacent the lower edge of the inner wall sheet and the other row of apertures terminate below the upper row of the apertures in the outer wall sheet so that all of the apertures 44 connect with a duct 47 that is formed within the compartment 43 by an angle 48 having a horizontal flange 49 welded to the inner wall sheet above the upper row of openings and having a vertical flange 50 welded to the top face of the horizontal flange 49 as shown in Fig. 2. The duct extends the full length of the respective coffer-dam sections and has its ends closed by the plate portions 28 of the respective connecting members.

The ducts thus formed are supplied with a pressure fluid through a duct 51 that extends upwardly through suitable openings in the respective flanges 11, 12 and 13 and which has a threaded terminal 52 that is adapted to be connected by a suitable duct 53 leading to a source of supply. Also formed in the compartment 23 and supported upon the flange 10 immediately

adjacent the outer wall of each coffer-dam section is a duct 54 having a plurality of apertures 55 through which a pressure fluid is discharged into the chamber for outlet through the outer openings 40 as later described. The perforated duct 54 is supplied with pressure fluid through a duct 56 leading upwardly through the flanges 11, 12 and 13 which is connected with a supply duct 57.

10 The compartment 23 is connected with the compartment 25 by a duct 58 having its ends welded in suitable openings formed in the flanges 11 and 12 as indicated at 59 and 60 (Fig. 3). The compartments 25 and 23 of each coffer-dam section are thus interconnected for flow of a liquid therebetween as later described. Each compartment 23 is also provided with an air jet pump indicated at 61 (Fig. 3) to which is connected an air supply duct 62 and a liquid discharge duct 63 which ducts extend upwardly through suitable openings in the flanges 11, 12 and 13 and adapted to be connected through ducts 64 and 65 respectively leading to a source of air supply and a liquid disposal, the pump 61 being used for a purpose later described.

15 The next upper compartment 24 of each coffer-dam section has the outer wall thereof provided with a plurality of jet openings 66 covered on the inner face of the wall by a plurality of layers of screen 67 that are retained in position by a plate 68 having apertures 69. The plate 68 is preferably welded in position similar to the other plates previously described.

20 The compartment 24 is also provided with a duct 70 that is supported on the flange 11 adjacent the outer wall and which is provided with a plurality of jet outlets 71. Each duct 70 is supplied with a pressure fluid through a duct 72 that extends upwardly through suitable openings in the flanges 12 and 13 respectively to be connected with an extension duct 73. The upper compartment 25 is adapted to be connected with an extension duct 74 which is secured to a nipple 75 mounted in the flange 13 and which discharges into the compartment 25 as best shown in Fig. 3. The flange 13 of the upper angle member of each section may be provided with a spaced series of bolts 76 having upwardly extending shanks 77 to which are connected inturned flanges 78 of caisson plate sections 79 having flange side edges 80 and 81 adapted to be connected by slip joints similar to the sliding joints of the coffer-dam sections or which are adapted to be clamped together by bolts 82 to form a caisson which is lowered with the coffer-dam. The caisson sections may be added to so that they extend to the top of the formation and form an enclosure through which the soil within the coffer-dam is excavated upon final setting of the coffer-dam.

25 In using the coffer-dam the sections are transported to the site of operations and one section is stood in vertical position with the lower cutting edge thereof supported on the surface of the ground, for example, on the bed of a stream into which the coffer-dam is to be placed and the other section is supported in proper relation so that the T-shaped flanges and ribs of the connecting members of one section register with the grooves of the complementary connecting members of the other section whereupon the section is lowered into position until the cutting edge thereof also rests upon the bed of the stream. The sections when thus related form a circular coffer-dam which encircles the site of the shaft to be excavated.

The caisson extensions may be applied and secured to the sections thus placed by the bolts 16. The duct extensions 73 and 57 are connected with the projecting threaded ends of the ducts 72 and 56 of each coffer-dam section so that liquid under pressure may be discharged into the chambers 23 and 24 from which the liquid is discharged under pressure through the jet openings for flow upwardly alongside the outer wall of the coffer-dam sections to displace and move upwardly the soil into which the coffer-dam is to be sunk. Simultaneously jets of liquid may be discharged through the openings 44 to effect a similar upflow of liquid and soil along the inner wall 5. The compartments 23, 24 and 25 fill with liquid which adds weight in cooperation with the excavating action of the jets to effect sinking of the coffer-dam to its desired position. When the coffer-dam is in its desired position air under pressure is admitted through the pipe extension 14 for displacing the water from the upper compartment 25 and into the lower compartment through the pipe 58 and from the lower compartment through the apertures 40. As the compartments empty the air is discharged through the jet opening to hold back the external liquids which might tend to pass under the coffer-dam. Similar jets of air may be discharged through the openings 44 into the interior of the coffer-dam and the water may be pumped from the interior of the coffer-dam by any suitable means (not shown) to dry up the core. The air pressure may be maintained while the soil of the core is being excavated to permit installation of a pier or other structure for which the shaft is formed. In case of a concrete pier, the form may be constructed within the coffer-dam and the concrete poured, after which the coffer-dam sections may be raised by lifting one of the sections out of interlocking relation with the other section. The other section may then be removed so as to permit the formation to settle in and around the pier as the sections are raised for reuse at another site of operations.

The construction shown in Fig. 4 corresponds with the structure as above described but the lower compartment 23 is provided with suitable refrigerating coils 83 to freeze the liquids immediately surrounding the lower edge of the coffer-dam sections to further prevent leakage of external water into the coffer-dam and further assist in drying out of the interior formation to facilitate removal thereof.

A coffer-dam constructed as described has many uses such as the sinking of wells in which case the pump 61 may be used for removing water which flows from the water producing formation into which the coffer-dam is sunk into the compartment 23 through the apertures 40 and 44. The coffer-dam may also be used for the sinking of oil and gas wells through loose earth formations to the solid formations. It may also be used as an agitator for dredging.

While I have described the coffer-dam as operating in a vertical direction, it is also obvious that it may be turned on its side for lateral tunneling. It is also obvious that the coffer-dam may be constructed in various shapes and sizes and composed of as many interlocking sections as desired without departing from the spirit of the invention.

From the foregoing it is obvious that I have provided a coffer-dam structure that is of simple and inexpensive construction for the removal of

the interior formation without the use of pressure chambers, air locks and the like.

What I claim and desire to secure by Letters Patent is:

- 5 1. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, means for supplying a pressure medium to said duct means separate from the liquid supply means to retard flow of liquid tending to flow under said wall and into the coffer-dam, and means connected with the upper compartment for introducing air under pressure to said compartment for displacing said liquid to control sinking rate of the wall.
- 10 2. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 15 3. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 20 4. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 25 5. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 30 6. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 35 7. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 40 8. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 45 9. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 50 10. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
- 55 11. An apparatus of the character described including a wall forming a coffer-dam, said wall having inner and outer sheets and horizontally arranged connecting members spaced apart and interconnecting the inner and outer sheets to form separate inner compartments one above the other with the upper compartment being closed and the lower compartment having outlets in the outer sheet for discharge of pressure fluids from the lower compartment, means for supplying liquid under pressure to the lower compartment for discharge through said outlets to effect sinking of the wall in a soil formation, a flow connection between said compartments for supplying liquid to the upper compartment to add weight to the wall for facilitating sinking thereof, means within the lower compartment for cooperating with the inner sheet for forming a duct separate from the compartment and said inner sheet having apertures in direct connection with the duct, and means for supplying a pressure medium to said duct separate from the liquid supply means to retard flow of liquid tending to flow under said wall into the coffer-dam.
